LANTERN

Robert A. Currie, Syracuse, N. Y., assignor to
 R. E. Dietz Company, New York, N. Y.

Application April 28, 1937, Serial No. 139,579

7 Claims. (Cl. 240—27)

This invention relates more particularly to improvements in the pivotal connections for the carrying bails or handles of tubular lanterns.

The usual tubular lantern is made with upright frame or air tubes at opposite sides of the lantern through which air for combustion is supplied to the lantern burner, and as commonly constructed, these air tubes have inbent or inwardly extending upper portions connected to a shell or part at the top of the lantern frame and inbent or inwardly extending lower portions connected with an air chamber wall or part at the lower portion of the lantern frame. Ordinarily, the handles or wire bails for carrying the lanterns are pivotally connected to the upper portions of the air tubes by hooking the bent or hooked lower ends of the legs of the bail into holes in the outer side wall portions of the air tubes. The bails are commonly made of relatively stiff or spring wire, and their pivot hooks are so shaped as to normally prevent accidental or unintentional disengagement of the ends of the bail from the pivot holes. However, the bails frequently become deformed or bent out of their original shape in the handling and use of the lanterns, particularly if the bail wire is relatively soft or pliable, or the pivot holes in the walls of the tubes become enlarged by wear, with resulting inconvenience or damage to the lanterns, or their loss. In the use of such lanterns on motor trucks, on the rear end or other portion of which they may be hung by their bails, breakage and loss of the lanterns, because of the bails becoming detached, due to vibrations of the moving trucks, are so frequent as to be a serious loss or objection.

One object of my invention is to provide a pivotal connection for the bails or handles of tubular lanterns which will reliably prevent unintentional disconnection of the bail from the lantern.

Other objects of the invention are to provide an improved pivotal connection for the bails or handles of tubular lanterns, which is of simple and inexpensive but strong and durable construction, and will prevent unintentional disconnection of the bails from the lanterns; which is constructed so that the bail will be releasably retained in either or both of its upright carrying and inoperative folded positions; and which has the other features of improvement and advantage hereinafter described and set forth in the claims.

The accompanying drawing illustrates different structural embodiments of my invention.

Fig. 1 is a front elevation of a tubular lantern of one construction embodying my invention.

Fig. 2 is an enlarged sectional elevation of the upper portion of one of the air tubes showing the pivotal connection for the bail.

Fig. 3 is a sectional plan through the air tube on line 3—3, Fig. 2.

Figs. 4 and 5 are fragmentary sectional elevations respectively on lines 4—4 and 5—5, Fig. 2, and respectively showing the outer and inner ends of the bearings for the bail pivots.

Fig. 6 is a sectional elevation similar to Fig. 2, but showing the position of the parts when the bail hangs down.

Fig. 7 is a sectional elevation, similar to Fig. 2, but showing a slight modification of the invention.

Figs. 8 and 9 are sectional elevations on lines 8—8 and 9—9 respectively, Fig. 7.

Fig. 10 is a sectional elevation, similar to Fig. 7, showing another modification embodying the invention.

Fig. 11 is a sectional elevation on line 11—11, Fig. 10.

Describing first the embodiment of the invention illustrated in Figs. 1—6 of the drawing, the lantern, with the exception of the construction of the pivotal connections for the bail, is of usual and well known tubular lantern construction. The frame or air tubes 12 at opposite sides of the lantern have inbent or inwardly extending upper ends 13 which are fixedly connected to the side walls of the air chamber shell 14 at the top of the lantern frame, and inwardly extending or inbent lower ends 15, which are rigidly connected to the wall 16 of the air chamber at the top of the oil fount and surrounding the lantern burner.

The wire handle or bail 17 of the lantern straddles the upper end of the lantern frame, and the legs of the bail are provided with inbent pivot ends 18, each of which extends transversely through the adjacent air tube 12 through holes in the opposite or outer and inner wall portions of the tube. The bail pivots are prevented from disconnection from their pivot holes or bearings in the air tubes by suitable securing means at the inner ends of the pivots. For this purpose, the protruding inner ends of the pivots can be swaged, as shown at 19 in the drawing, bent upwardly, or provided with cotter pins or other suitable means which cannot pass through the pivot holes or bearings and thus prevent the pivots from being pulled out of their bearings or pivot holes.

In tubular lanterns as heretofore commonly

made, the bent or hooked ends of the bail are simply hooked into plain or eyeleted pivot holes through the outer wall portions of the air tubes, and because of the form or construction of the 5 air tubes or the attachment of the inwardly extending ends of the tubes to other frame parts of the lantern, it is impractical to form the ends of the hooks or pivots, which are located inside of the air tubes, so as to prevent the hooks or 10 pivots from being removed or disengaged from their pivot holes in the tubes, or to furnish the inner ends of the hooks or pivots with securing means for this purpose and, as before explained, the bails therefore can and frequently do become 15 disconnected from the lanterns in the use thereof.

By the described construction, however, in which the bail pivots extend completely through the air tubes, the inner ends of the pivots are exposed at the inner sides of the tubes where 20 they can be bent, swaged or otherwise formed or furnished with securing means which will prevent the pivots from being withdrawn from the holes in the tubes. Furthermore, by this construction, each pivot for the bail extends through 25 and is adapted to bear in widely spaced-apart holes or bearings in or on the opposite or outer and inner wall portions of the air tube, and this greatly reduces the wear on the edges of the 30 pivot holes or bearings, so that they will not become worn and enlarged in use and increase the possibility of the disconnection of the pivots from the tubes, as in the case of previous constructions, in which each bail pivot extends only through a hole in a single thin wall portion of the 35 tube.

Preferably the pivot holes in the air tubes are strengthened and reinforced by bearing eyelets or bushings for the bail pivots. In the constructions shown, with the exception of that illustrated 40 in Figs. 10 and 11, a long bearing eyelet or bushing 20 is shown extending transversely through each air tube with the ends of the bushing in the holes in the inner and outer wall portions of the tube, and being secured therein, 45 as by flanging the ends of the bushing 20 over the edges of the holes in the wall of the tube. These long bushings not only provide extended bearings for the bail pivots but also connect the inner and outer wall portions of the air tubes and thus brace and strengthen the tubes at the 50 pivotal connections for the bail.

In the modification shown in Figs. 10 and 11, separate eyelets 21 are secured in the holes in the inner and outer wall portions of each air tube. 55

As clearly shown in the drawing, the axes of the bail pivots 18 are not coincident with the axes of the bearings for the pivots, but are disposed at an angle or inclination thereto. For instance, 60 as shown in Fig. 2, the bail pivot bears against the inner and outer ends of the bushing 20 respectively above and below its axis when the bail is upright while, as shown in Fig. 6, the pivot bears against the corresponding ends respectively 65 below and above said axis when the bail hangs down. Thus, when the bail is swung from one to the other of its hanging and standing positions, the pivot is sprung or deflected up or down and the pressure of the pivot on the diagonally 70 opposite portions of the bushing resulting from the strain incident to such deflection of the pivot acts to releasably or yieldingly hold the bail against movement from its standing and hanging positions. When, therefore, the bail is swung up 75 to its standing position, for instance, it will re-

main standing unless it is pushed out of the standing position.

Preferably, one or both ends of each bushing 20 is or are deformed somewhat from circular shape so as to vertically elongate the end or ends, or form internal end depressions 22 at the top and bottom of the bushing which taper inwardly longitudinally of the bushing. Figs. 4 to 6 show the bushing thus deformed at both its inner and outer ends, while Fig. 7 shows such deformation at the outer end only of the bushing. With this deformation of the bushings, the pressure of pivots 18 in the depressions 22 will offer added resistance to the movement of bail, and better act to releasably hold it upright than if 15 the ends or parts of the bearings engaged by the pivots were circular.

The separate eyelets shown in Fig. 10 are similarly deformed to provide upper and lower depressions 23, which act in the same manner to 20 resist movement of the bail from its standing or hanging positions.

I claim as my invention:

1. A lantern comprising frame tubes at opposite sides thereof, a carrying bail for the lantern, 25 and pivotal connections between the bail and lantern frame comprising pivots projecting from the legs of the bail transversely through said side tubes, each tube having spaced bearings at its opposite side wall portions in which the pivot passing through said tube engages, said pivot and bearings being normally disposed with their axes somewhat out of alignment so that the pivot bears against one bearing above and the other bearing below its center whereby the pivot is strained 30 by swinging the bail from one of its positions to another and acts to releasably hold the bail in said position.

2. A lantern comprising frame tubes at opposite sides thereof, a carrying bail for the lantern, 40 and pivotal connections between the bail and lantern frame comprising a pivot bushing extending transversely through each tube from side to side thereof, pivots projecting from the legs of the bail through said bushings, and means on the 45 ends of the pivots which engage the adjacent ends of the bushings and prevent disengagement of the pivots from the bushings.

3. A lantern comprising frame tubes at opposite sides thereof, a carrying bail for the lantern, 50 and pivotal connections between the bail and lantern frame comprising a pivot bushing extending transversely through each tube and secured at its ends in holes in opposite sides of the tube, pivots projecting from the legs of the bail through 55 said bushings, and means on the ends of the pivots which engage the adjacent ends of the bushings and prevent disengagement of the pivots from the bushings.

4. A lantern comprising frame tubes at opposite sides thereof, a carrying bail for the lantern, 60 and pivotal connections between the bail and lantern frame comprising a pivot bushing extending transversely through each tube from side to side thereof, pivots projecting from the legs of the bail through said bushings, said pivots and bushings extending at angles to each other such that the pivots bear against opposite ends of the bushings respectively above and below the axes of the bushings, whereby the pivots are strained by 65 swinging the bail to a standing position and act to releasably hold the bail standing.

5. A lantern comprising frame tubes at opposite sides thereof, a carrying bail for the lantern, 70 and pivotal connections between the bail and 75

- lantern frame comprising a pivot bushing extending transversely through each tube from side to side thereof, pivots projecting from the legs of the bail through said bushings, said pivots and bushings extending at angles to each other such that the pivots bear against opposite ends of the bushings respectively above and below the axes of the bushings, whereby the pivots are strained by swinging the bail to a standing position and act to releasably hold the bail standing, the end portions of the bushings against which the pivots bear being depressed to increase the bail-holding action of the pivots.
- 5 6. A lantern comprising frame tubes at opposite sides thereof, a carrying bail for the lantern, and pivotal connections between the bail and lantern frame comprising a pivot bushing extending transversely through each tube from side to side thereof, pivots projecting from the legs of the bail through said bushings, said pivots and bush-
- 10 15 20

ings extending at angles to each other such that the pivots bear against opposite ends of the bushings respectively above and below the axes of the bushings, whereby the pivots are strained by swinging the bail to a standing position and act to releasably hold the bail standing, the end portions of the bushings against which the pivots bear being depressed to increase the bail-holding action of the pivots.

5 6 10 15 20 25 30

7. A tubular lantern comprising a frame having air tubes at its opposite sides, a carrying bail for the lantern, and pivotal connections between the bail and lantern frame comprising pivots projecting from the bail legs transversely through said air tubes through holes in the opposite sides of each tube, bearing eyelets in said holes, one eyelet of each tube having a depression in which the related pivot is pressed by the spring action of the bail to releasably hold the bail in one of its positions.
